US00D913579S

(12) **United States Design Patent** (10) **Patent No.:** **US D913,579 S**
Bowen et al. (45) **Date of Patent:** **** Mar. 16, 2021**

(54) **VAPORIZER DEVICE WITH CARTRIDGE**

(71) Applicant: **JUUL Labs, Inc.**, San Francisco, CA (US)

(72) Inventors: **Adam Bowen**, San Mateo, CA (US);
James Monsees, San Francisco, CA (US); **Steven Christensen**, Burlingame, CA (US); **Joshua Morenstein**, San Francisco, CA (US); **Christopher Nicholas Hibmacronan**, Oakland, CA (US)

(73) Assignee: **JUUL Labs, Inc.**, San Francisco, CA (US)

(**) Term: **15 Years**

(21) Appl. No.: **29/707,225**

(22) Filed: **Sep. 26, 2019**

Related U.S. Application Data

(63) Continuation of application No. 29/650,601, filed on Jun. 7, 2018, now Pat. No. Des. 861,975, which is a continuation of application No. 35/001,169, filed on Jul. 28, 2016 (U.S. filing date under 35 U.S.C. 384), and having an international filing date of Mar. 11, 2016, now Pat. No. Des. 825,102.

(57) **CLAIM**

The ornamental design for a vaporizer device with cartridge, as shown and described.

DESCRIPTION

FIG. 1 is a top, rear, and right side perspective view of a vaporizer device with cartridge showing a first embodiment of our design;

FIG. 2 is a top view thereof;

FIG. 3 is a left side view thereof;

FIG. 4 is a rear view thereof;

FIG. 5 is right side view thereof;

FIG. 6 is a front view thereof; and

FIG. 7 is a bottom view thereof.

FIG. 8 is a top, rear, and right side perspective view of a vaporizer device with cartridge showing a second embodiment of our design;

FIG. 9 is a top view thereof;

FIG. 10 is a left side view thereof;

FIG. 11 is a rear view thereof;

FIG. 12 is right side view thereof;

FIG. 13 is a front view thereof; and

FIG. 14 is a bottom view thereof.

FIG. 15 is a top, rear, and right side perspective view of a vaporizer device with cartridge showing a third embodiment of our design;

FIG. 16 is a top view thereof;

FIG. 17 is a left side view thereof;

FIG. 18 is a rear view thereof;

FIG. 19 is right side view thereof;

FIG. 20 is a front view thereof; and,

FIG. 21 is a bottom view thereof.

The dash-dash broken lines illustrate portions of the vaporizer device with cartridge that form no part of the claimed design.
